Attorneys.

UNITED STATES PATENT OFFICE.

WALDO ALTON RICH, JR., OF FRAMINGHAM, MASSACHUSETTS, ASSIGNOR TO DENNISON MANUFACTURING COMPANY, OF FRAMINGHAM, MASSACHUSETTS, A CORPORATION OF MASSACHUSETTS.

DIE.

1,254,732.

Specification of Letters Patent. Patented Jan. 29, 1918.

Application filed April 18, 1917. Serial No. 162,899.

To all whom it may concern:

Be it known that I, WALDO A. RICH, Jr., a citizen of the United States, and resident of Framingham, in the county of Middlesex and State of Massachusetts, have invented new and useful Improvements in Dies, of which the following is a specification.

This invention relates to dies such as are commonly used in printing of many kinds, 10 as stamps for impressing sealing wax and like purposes. Its object is to provide a die comprising a plurality of separable sections adapted to be manufactured in quantities and carried in stock, each section having thereon a complete letter or other character, either in intaglio or relief as desired, whereby a die having a plurality of characters may be readily assembled and made ready for use, thus eliminating the necessity of cutting a particular die to meet a 20 particular requirement.

As illustrative of my invention I have shown a stamp or die of the kind commonly employed to impress a sealing wax seal, but 25 it will be understood that this embodiment of the invention is illustrative merely. The most desirable sealing wax stamps are commonly cut with a plurality of letters, usually the three initials of the user, and each 30 such stamp or die has to be specially cut to order; for it is obviously a commercial impossibility for retailers to carry in stock stamps having all combinations of letters. The cutting of such a die or stamp is relatively 35 expensive, so that many persons while desirous of such stamps, are forced to content themselves with the familiar single letter, stock, stamp which, whatever its artistic merit, necessarily lacks the individuality 40 and personal association which is of the essence of such a stamp.

Again, these stamps or dies are largely purchased as gifts at seasons when, because of pressure of work or lateness of the order, 45 it is impossible to furnish a specially cut die within the time the gift must be presented, so that prospective givers are unable to obtain the particular stamp desired unless the order is placed far in advance.

50 By the use of my invention these difficulties are eliminated and retail dealers are enabled to carry in stock, and furnish on call at a relatively low price, stamps or dies

having any usual combination of letters or other characters desired.

Referring to the drawings which illustrate an embodiment of my invention,—

Figure 1 is a face view of a stamp or die embodying the invention;

Fig. 2 is a side view, partly in section 60 and partly in elevation; and

Fig. 3 is a plan view of the top of the die, the handle being removed.

My improved die consists of a plurality of separable sections A, each having a complete character thereon, which may be in intaglio or relief, as desired, or as the intended use requires. In the die shown, three such sections are employed, each having a complete letter in intaglio, the said sections being dove-tailed, as clearly shown in Fig. 2, with the tenons on the center section and the mortises on the end sections. While this means of connecting the sections is preferred, it will be understood that said sections may be united by any suitable complementary connecting means located on their juxtaposed edges.

Each section A is provided upon its top face with a transverse recess B, the marginal edges of said recesses being in register when the sections are assembled. In the transverse recess thus provided is a locking bar C which extends from end to end of said recess and is flush with the top face of 85 the die. The central die section has an aperture D preferably screw-threaded as shown, and the bar C has an aperture registering with said die aperture D. The projection or screw S upon the handle H extends 90 through the bar aperture into the aperture D, thus retaining said bar in locking position to hold said sections against relative movement.

Effectively to conceal the joints between 95 the die sections, it may be desirable under some conditions of use to provide a pattern upon the working face of the die, the joints between said sections forming an element of the pattern. Thus the working face of the 100 die may be provided with markings P which extend parallel to the die joints so that said joints form an element of the pattern thus made and are effectively concealed.

It will, I believe, be clear that by the use 105 of my invention above described dealers are

enabled to carry in stock die sections, each with a complete letter or other character, and can readily assemble these sections to provide the particular stamp or die required 5 by the customer. Being made in quantities these sections can be furnished at a comparatively low cost, so that the particular stamp desired can not only be immediately furnished but at a cost much lower than 10 would be possible if the die were specially cut.

The advantages of the invention to printers will also be readily apparent; for by its use they need carry in stock but a relatively 15 small number of die sections, which can readily be assembled to make a particular die and as readily disassembled upon completion of the work, thus eliminating the necessity for the cutting of special dies which 20 become useless upon completion of the particular work for which they were made.

I claim:

1. A die comprising separable interlocking sections and unitary means wholly disposed upon the top face of the die to lock all of said sections against relative movement.

2. A die comprising separable interlocking sections and means extending across all 30 of the sections and wholly disposed upon the top face of the die to lock said sections against relative movement.

3. A die comprising separable sections having complemental locking means on their 35 juxtaposed edges only, and means wholly disposed on the top face of the die to lock said sections against relative movement.

4. A die comprising three separable sections, the center section having locking 40 means on its opposite side edges, and the end sections having complemental locking means upon one edge only, and means wholly disposed on the top face of the die to lock said sections against relative movement.

45 5. A die comprising separable sections,

and means to lock said sections against relative movement comprising a unitary transverse locking bar disposed upon the top face thereof.

6. A die comprising separable interlocking sections having a transverse recess in their top faces, and means to lock said sections against relative movement comprising a locking bar in said recess. 50

7. A die comprising separable interlocking sections having a transverse recess in their top faces, and means to lock said sections against relative movement comprising a locking bar in said recess, and means engaging said bar to retain it in locking position. 55

8. A die comprising separable interlocking sections, and means to lock said sections against relative movement comprising a transverse locking bar, and means extending through said bar into a die section to retain said bar in locking position. 60

9. A die comprising separable interlocking sections, one of said sections having a screw-threaded aperture, a transverse locking bar to lock said sections against relative movement, and a screw extending through said bar into said aperture to retain said bar in locking position. 70

10. A die comprising separable interlocking sections having a transverse recess, and means to lock said sections against relative movement comprising a locking bar in said recess, and means extending through said bar into a die section to retain said bar 75 in locking position. 80

11. A die comprising separable interlocking sections having a transverse recess, a locking bar in said recess, and a handle having a projection extending through said bar 85 into a die section to retain said bar in locking position.

Signed by me at Framingham, Massachusetts, this 16th day of April, 1917.

WALDO ALTON RICH, JR.
